UNITED STATES PATENT OFFICE

2,092,436

APPARATUS FOR RE-REFINING USED OIL

John H. Vital, New Orleans, La.

Application March 20, 1936, Serial No. 69,960

1 Claim. (Cl. 196—106)

This invention relates to oil refining and processes, and more particularly to the recovery of lubricating oil.

An object of this invention is the provision of an improved process by means of which lubricating oil which has been in use in engines or motors may be re-refined and reconditioned and any ingredients in the form of solids, liquids or acids removed therefrom so that the oil will be returned to substantially its original viscosity and its original condition.

Another object of this invention is to provide an improved process and means therefor by which any light fraction or acid which may have combined with the oil will be readily removed, the lighter fraction or fractions being taken out of the oil in the form of vapor which may be subsequently treated for recovery and separation of the ingredients incorporated in such lighter fractions.

A further object of this invention is the provision of a relatively simple process and means therefor which is so constructed that at desired times the apparatus embodied in the process may be easily and quickly cleaned.

Still another object of this invention is an improved process and means therefor by which oil may be treated in a substantially continuous process, the means being such that a relatively small plant is capable of treating a relatively large quantity of oil.

With the foregoing and other objects in view, the invention will be more fully described hereinafter, and will be more particularly pointed out in the claim appended hereto.

In the drawings, wherein like symbols refer to like or corresponding parts throughout the several views:

Figure 1 is a fragmentary front elevation of an oil refining and recovery means embodied in the present invention.

Figure 2 is a fragmentary rear elevation of the device.

Figure 3 is a sectional view taken on the line

45 3—3 of Fig. 1.

Figure 4 is a transverse sectional view taken through one of the recovery or refining stills.

Referring to the drawings, wherein like symbols refer to like parts throughout the several views, the numeral 10 designates generally a still in the form of a substantially horizontally disposed cylindrical receiver 11 provided with flanged opposite ends 12 and 13 against which heads or plates 14 and 15, respectively engage. The head 14 is preferably the front head or wall, and is secured to the flange 12 by means of bolts or like fastening devices so that when desired this head or wall may be readily removed. The head 15 constitutes the rear head or wall and 55 engages against the flange 13, being secured

thereto by means of bolts or like fastening devices.

Preferably the receiver 11 is disposed on a slight angle to the horizontal so that the oil and other material placed therein will gravitatingly run toward the front head or wall 14 and into an outlet connection 16 having a valve 17 connected thereto. The receiver 10 is provided with an intake 18 adjacent the top thereof, and preferably at a point between the ends thereof, and the material discharged into the receiver 10 enters through this intake 18. A steam pipe 19 is connected to the head 14 at a point adjacent the bottom thereof so that steam of a suitable temperature may be discharged into the receiver 10 to facilitate the vaporization of the lighter fractions contained in the oil, in addition to maintaining the oil at the proper temperature.

The front wall or head 14 is provided with a sight glass 20 so that the proper quantity of oil may be maintained in the receiver, and a thermometer 21 is also connected to the front wall or head 14 for the purpose of determining the temperature of the oil. A pressure gauge 22 is carried by the head 14 to determine the pressure within the receiver 10. A burner 23 is disposed below the receiver and is used to initially heat the oil in this upper receiver 10 during the start of operations, it being understood that after the oil in the receiver 10 has been heated to the proper temperature for initial treatment thereof this burner 23 is then cut off and heat derived as hereinafter indicated.

Vapors arising from the oil in the receiver 10 are taken off through a vapor line 24 which is connected to a suitable suction means (not shown) and these vapors may then be treated in any suitable manner for recovery of the various fractions contained therein. When the oil is discharged into the receiver or still 10, a filtering means in the form of fuller's earth is also discharged into the receiver, and the entire mass is then agitated at the same time that heat is applied thereto by means of an agitator comprising a pair of elongated blades 25 which are secured to radial arms 26 carried by a hub 27, there being a hub 27 and radial arms 26 adjacent each end of the receiver 10. The hubs 27 are fixed to a drive shaft 28 which is journaled in the heads 14 and 15. The forward end of the shaft 28 engages a bearing in the form of a stuffing box or gland 29 and terminates within a cap 30 carried by the stuffing box 29. The other end of the shaft 28 extends through a stuffing box or gland 31 carried by the head 15, and a sprocket wheel 32 is secured to the projecting end of the shaft 28.

Preferably the longitudinal blades 25 substantially contact with the inside surface of the receiver 10, and the radial arms 26 also substantially engage with the inside surface of the heads 14

and 15 so that no solids or the like may accumulate within the receiver. The agitator, comprising the blades 25 and the arms 26, may be removed from the receiver by loosening the head 5 15 and drawing the agitator out through the rear of the receiver.

When the oil is drawn from the still 10 by opening the valve 17, the oil will pass through a branch pipe 33 which is connected to the outlet pipe 16, 10 and this pipe 33 is connected to intake pipes 34 and 35 which are connected to fractionating stills 36 and 37, respectively, which are disposed below the upper or initial fractionating still 10. The upper still 10 is supported in an elevated position 15 by means of beams 38 and 39 which rest on top of the lower stills 36 and 37.

The lower stills 36 and 37 are supported on beams 40 and 41 which rest on the upper ends of supporting posts 42 and 43, respectively. A casing 20 or housing 44 engages about the stills 10, 36 and 37 and encloses substantially all of these stills with the exception of the ends thereof, as shown in Figs. 1 and 3. The lower stills 36 and 37 are of identical construction, and in fact are identical 25 with the upper still 10, having rotatable agitating means 45 and 46, respectively, disposed therein which are mounted on shafts 47 and 48, respectively. Burners 49 and 50 are provided for the stills 36 and 37, respectively, and after the 30 device has been initially heated, the upper burner 23 may be cut off and the heat from the lower burners 49 and 50 utilized, through the medium of the casing 44 to keep the upper still at the proper temperature.

35 The still 36 is provided with a dome 51 which is connected thereto by means of a pipe 52, and the vapors entering this dome 51 are drawn off through an outlet or suction line 53. The still 37 also has a dome 54 connected thereto by means 40 of a pipe 55, and the vapors entering the dome 54 are drawn off through an outlet or suction line 56.

The shaft 47 has a sprocket 57 secured to the 45 rear end thereof, and the shaft 48 has a sprocket 58 secured to the rear end thereof, and a flexible member 59 in the form of a chain or the like is trained over the sprockets 32, 57 and 58, and a driving member 60 engages a suitable sprocket 50 secured to one of the shafts, and in the present instance a sprocket secured to the shaft 47. The driving belt or chain 60 may be connected to a suitable source of power supply (not shown) so that the agitating members in the various stills or receivers may be rotated at the desired speed.

55 The ends or heads of the stills may be suitably braced by means of braces 61 in the form of angle bars or the like so that the pressures within the stills will not distort the heads or end walls thereof and thus prevent the cleaning of the end walls by means of the radial arms of the agitating members.

The oil discharged from the upper still 10 may 60 be discharged into either or both of the lower stills 36 and 37, by means of valves 62 and 63, 65 the valve 62 controlling the passage of oil to the still 36 and the valve 63 controlling the passage of oil to the still 37. The stills 36 and 37 have outlets 64 and 65, respectively, and after proper treatment of the oil in either or both of these stills, the oil together with the filtering means is removed through the outlets 64 and 65 and then discharged into settling tanks where the final

process in the cleaning of the oil takes place.

In the use and operation of this device, the untreated oil, together with a suitable filtering means is discharged into the upper still 10 through the intake pipe 18, and the mass heated 5 by the steam from the steam line 19 in addition to heat from the burner 23 and heat from the lower burners 49 and 50 which rises within the casing 44. While the heating of the oil is in process, the shaft 28 is rotated so that the agitating means comprising the blades 25 and the arms 26 will prevent settling of the filtering means incorporated in the oil and disposed in the receiver 16, in addition to preventing the accumulation of any coke or like deposits on the interior of the receiver 10.

A considerable number of relatively light fractions will arise as vapor in the receiver 10 and will be drawn out through the vapor line 24, 20 while the residue will then be discharged into one or both of the heavier fractionating stills 36 and 37, depending upon the quantity of oil which is being handled through the device. The material in the lower stills 36 and 37 will be heated additionally by the burners 49 and 50, and by the 25 steam discharged by the steam lines 66 and 67, respectively. The higher temperature applied to the oil in the lower stills will vaporize the heavier fractions not removed in the upper still 10, and the remaining oil will then be free from acids and 30 other fluids which accumulated therein during the use of the oil as a lubricating agent. It is, of course, understood that the filtering agent used in this process will remove any of the solids embodied in the oil and after the reconditioned oil 35 has been drawn off from the lower stills 36 and 37, the filtering agent may be readily separated from the oil through either settling or some other conventional process.

It is obvious that various changes and modifications may be made in the details of construction and design of the above specifically described embodiment of this invention without departing from the spirit thereof, such changes and modifications being restricted only by the scope of the 45 following claim.

What is claimed is:

An oil refining means comprising a plurality of triangularly arranged cylindrical still members, a housing enclosing said members, the 50 lowermost of said members being disposed in substantially the same horizontal plane, a feed pipe connecting the lowermost members together, a discharge pipe connecting the uppermost of said members with said feed pipe, a pair of valves in 55 said feed pipe on opposite sides of said discharge pipe, a valve in said discharge pipe, a feed line connected to the uppermost of said members, individual vapor drawoff means for each of said members, a heating means in said housing beneath each member, each of said members having flat end walls, a shaft journaled in each member, a scraping member secured to each shaft, said scraping member including diametrically opposed parallel blades contacting with the cylindrical surface of the still member, and a pair 65 of end wall scraping blades secured to said shaft and to the ends of said first blades and contacting throughout the length thereof with the inner faces of said end walls, and means for rotating 70 said shafts in unison.

JOHN H. VITAL.
